(57) **CLAIM**

I claim the ornamental design for a male chastity apparatus, as shown and described.

DESCRIPTION

FIG. 1 is a right front perspective view of a male chastity apparatus showing our new design in a fully assembled state.

FIG. 2 is a right side view thereof.

FIG. 3 is a right back perspective view thereof.

FIG. 4 is a back view thereof.

FIG. 5 is a left back perspective view thereof.

FIG. 6 is a left side view thereof.

FIG. 7 is a left front perspective view thereof.

FIG. 8 is a front view thereof.

FIG. 9 is a right front perspective view of the shaft cage component of the male chastity apparatus of FIG. 1.

FIG. 10 is a right side view thereof.

FIG. 11 is a right back perspective view thereof.

FIG. 12 is a front view thereof; and,

FIG. 13 is a bottom view thereof.
